Primary Examiner — Manpreet Matharu*Assistant Examiner* — Suzanne Tisdell(74) *Attorney, Agent, or Firm* — CARR Law Firm PLLC(57) **CLAIM**

We claim the ornamental design for a dual battery charger, as shown and described.

DESCRIPTION

FIG. 1 is a top, right, front perspective view of a battery charger;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the battery charger that form no part of the claimed design.

1 Claim, 5 Drawing Sheets(56)
